UNITED STATES PATENT OFFICE.

EMILE GÉRARD, OF LIMOGES, FRANCE, ASSIGNOR TO GÉRARD, DUFRAISSEIX
& ABBOT, OF NEW YORK, N. Y.

DESIGN FOR A PLATE OR DISH.

SPECIFICATION forming part of Design No. 27,528, dated August 17, 1897.

Application filed January 6, 1897. Serial No. 618,209. Term of patent 14 years.

To all whom it may concern:

Be it known that I, EMILE GÉRARD, a citizen of the French Republic, residing at Limoges, Department of Haute-Vienne, France, have invented and produced a new and original Design for Plates or Dishes, of which the following is a specification, reference being had to the accompanying drawing, which forms part hereof and wherein the figure represents a plate or dish in plan embodying my design.

The characteristic features of my design consist of one or more leaf-like bands around the plate or dish and one or more leaf-like garlands having floral sprays projecting to each side thereof.

In the drawing, A represents the body of a plate or dish, around which are one or more sinuous leaf-like bands *a*, each of which com-

prises a fine sinuous stem having similar leaf-like ornaments projecting from opposite sides thereof, each of said bands being of the same configuration on opposite sides of the longitudinal median lines thereof. Ornamental garlands *B* are arranged at intervals around the plate or dish, and from each side of each of these garlands project floral sprays *b*. Other floral sprays *c* are shown disposed between the leaf-like garlands and projecting floral sprays.

What I claim is—

The design for a plate or dish, substantially as shown and described.

EMILE GÉRARD. [L. S.]
